**PUSHBUTTON-CONTROLLED OVERLOAD
CIRCUIT BREAKER**

Jakob Ellenberger, Altdorf, near Nurnberg, Germany, assignor to Firma Ellenberger & Poensgen G.m.b.H., Altdorf, near Nurnberg, Germany, a German firm

Filed Oct. 22, 1965, Ser. No. 500,720

Claims priority, application Germany, June 2, 1965,
E 29,441

12 Claims. (Cl. 335—35)

The present invention relates to a pushbutton-controlled overload circuit breaker which is provided with a thermal release and/or an electromagnetic release and also with a trip-free release, and further with a contact bridge. When the pushbutton of this circuit breaker is being depressed and a control rod which is rigidly secured to the pushbutton is moved accordingly, a carrier member on the control rod moves the contact bridge to the on position in which the carrier member is disconnected from the contact bridge. In my previous Patent No. 2,895,028, I have described and claimed an overload circuit breaker of the above-mentioned type which is designed so as to have very small outer dimensions, may be switched on and off instantaneously, and may in addition be switched off by hand by means of an additional release button. The contact bridge of this circuit breaker is slideable as well as pivotable on the control rod which is rigidly secured to the pushbutton and consists of insulating material, and the trip-free release is effected by a compression spring which is mounted on the control rod between the contact bridge and the carrier member.

In actual practice it has been found that this overload circuit breaker has the disadvantage that, if an additional pressure is exerted upon the pushbutton when it is already depressed and the contact bridge is in its on position in which the contact pressure is produced by the cut-off spring which acts upon the pushbutton, this spring is compressed and thereby rendered ineffective. Therefore, when the pushbutton is in this depressed position, the contact pressure is produced merely by the other spring which is adapted to effect the trip-free release of the circuit breaker. The carrier member on the control rod which is acted upon by this trip-free release spring is then likewise moved so that this spring is released to a certain extent and the contact pressure is thereby further reduced. The result of such a low contact pressure may be, especially if the circuit breaker is employed for currents of a high amperage, that the resistance between the contact bridge and the associated fixed contacts might increase so highly that these parts may be heated to such high temperatures that they might be scorched or freeze together.

It is an object of the present invention to provide an overload circuit breaker which is of the same type as, and possesses all of the advantages of the circuit breaker as described above and disclosed in detail in my previous Patent No. 2,895,028, but which improves this known circuit breaker by designing it so as to insure that, when the pushbutton is already depressed and the contact bridge is in its on position, the contact pressure will not be changed when an additional pressure is exerted upon the pushbutton. The overload circuit breaker according to the invention may therefore be employed especially for currents of high amperages. Another object of the invention is to design such an overload circuit breaker so as to have very small outer dimensions even though it is intended for high amperages, and to be of a simple construction which may be easily manufactured and assembled. A further object is to design the circuit breaker so that it may also be switched off by hand.

One important feature of the invention consists in mounting the contact bridge on a pivotable control level,

2

the pivot pin of which is slideable within the walls of the housing and adapted to be locked in a fixed position by a pivotable pawl when the contact bridge is in its on position. When this pawl is in its locking position, it is braced on a release lever which may be pivoted to an inoperative position when an excess current occurs. The control lever which is connected to the contact bridge is provided with a stop projection which, when the contact bridge is in its off position, is located within the area of motion of a carrier member which is mounted on the control rod which, in turn, is secured to the pushbutton. When the contact bridge is in its on position, this stop projection on the control lever is moved out of the area of motion of the carrier member. The control lever is acted upon by a compression spring which, when the pivot pin of the control lever is locked by the pawl in a fixed position, produces the necessary contact pressure of the contact bridge and, when the pivot pin of the control lever is released by the pawl, moves the control lever together with the contact bridge to the off position.

When the contact bridge is in the on position, the control lever is therefore located in a position in which its stop projection is outside of the area of motion of the carrier member on the control rod which is rigidly secured to the pushbutton. Therefore, if a further pressure is then exerted upon the pushbutton when the contact bridge is already in its on position, it will have no effect upon the control lever and thus also not upon the contact bridge and the contact pressure which is produced by the compression spring which acts upon the control lever. A change in the strength of the contact pressure which could occur in my previous circuit breaker as above referred to when the pushbutton was again depressed when the circuit breaker was already switched on can therefore not occur in the circuit breaker according to the present invention. The compression spring which acts upon the control lever produces a contact pressure of a high constant strength so that the contact resistance between the contact bridge and the fixed contacts is very small and any excessive heating of the contacts is prevented and the contacts are therefore prevented from scorching and fusing together so that the entire circuit breaker will therefore be properly operative for a very long time. Since the control lever and thus the contact bridge cannot possibly be affected by the pushbutton or the carrier member when the contact bridge is in its on position, a trip-free release will be attained when the control lever is released by the pawl under the action of the compression spring which acts upon the control lever.

Only relatively small forces are required to move the release lever to the position in which the pawl will no longer be supported thereon so that a trip-free release will then occur. These releasing forces may be so small because the pawl is merely braced on the release lever, preferably in a position vertical to the pivot axis of the release lever.

The above-mentioned as well as further objects, features, and advantages of the present invention will become more clearly apparent from the following detailed description thereof, particularly when read with reference to the accompanying drawings, in which

FIGURE 1 shows, partly in section, a side view of the circuit breaker according to the invention in the on position and with one part of the housing removed;

FIGURE 2 shows a detailed view of the pushbutton together with the control rod and the carrier member according to FIGURE 1;

FIGURE 3 shows a view of the same element as in FIGURE 2, but as seen from the left side thereof;

FIGURE 4 shows a view similar to FIGURE 1, but with the circuit breaker in the off position;

FIGURE 5 shows a view as seen in the direction of the arrow V in FIGURE 4;

FIGURE 6 shows a cross section which is taken in the direction perpendicular to the axis of the control lever, as seen from the left of FIGURE 4; while

FIGURE 7 shows a perspective view of the right upper part of the circuit breaker according to FIGURE 4.

As illustrated in the drawings, the overload circuit breaker according to the invention comprises a housing of insulating material which consists of two separate parts, namely, the part 1 into which the switch elements are inserted and another similar part, not shown, which is secured to and covers the part 1. Both parts of the housing are provided with recesses in which the various switch elements are held in their proper positions relative to each other, and both parts are secured to each other by rivets, preferably tubular rivets, which are inserted into corresponding bores 2 in both parts of the housing.

For connecting it to an electric circuit, the circuit breaker is provided with two terminal strips 3 and 4 and terminal screws 5 thereon. The inner end of terminal strip 3 carries a fixed contact 6 which is operatively associated with a contact 7 on a contact bridge 8. This contact bridge 8 has another contact 9 which, when the contact bridge is in its on position, as illustrated in FIGURE 1, engages upon a fixed contact 10 on a connecting bar 11 which is secured by a screw 12 to the housing part 1. This connecting bar 11 is bent three times at right angles and it is centrally slotted so that its front and rear parts are connected at their upper ends and together form a coil winding. Arm 13 of this bar 11, which, according to FIGURE 1, forms the front end thereof, is connected by a screw 14 to a part 15 which is electrically connected to the rear arm of the bimetal strip 16 which is likewise centrally slotted. The front arm of the slotted bimetal strip 16 is soldered or welded at 17 to one arm 4' of the slotted terminal strip 4, the other arm 4" of which is bent toward the right and secured by a screw 18 to the housing part 1. The slotted bar 11 and the slotted bimetal strip 16 form two coil windings through which the arm 20 of a magnet core 19 extends. This core 19 has another arm 21 which is provided with an extension 22 which projects at a right angle from the arm 21 and extends across the entire width of bar 11 above the upper end thereof.

As shown in FIGURE 1, the left end of arm 20 of the magnet core 19 has an upwardly bent extension 23. The magnetic circuit of core 19 may be closed almost entirely at the extensions 22 and 23 by an armature 24 which forms an arm of a release lever 26 which is pivotably mounted on a pin 25. This release lever 26 has another arm 27 into which there is screwed a setscrew 28 which has a small knob 29 of insulating material which is acted upon by the bimetal strip 16 when the latter is bent toward the right from its position as shown in FIGURE 1. As illustrated particularly in FIGURE 7, the rear arm 30 of the release lever 26 has a shoulder 31 upon which an arm 33 of a pawl 32 engages when this pawl is in its locking position, as shown in FIGURE 1. Pin 25 on which the release lever 26 is mounted carries a torsion spring 34, one arm 35 of which acts at 36 upon the pawl 32, while the other spring arm 37 acts upon the release lever 26. This torsion spring 34 tends to maintain the pawl 32 and the release lever 26 in the positions as shown in FIGURE 1. As illustrated particularly in FIGURE 6, pawl 32 is pivotably mounted on two rivets 38 at the inside of a metal frame 39 which is inserted into recesses of a corresponding shape in the two parts of the housing.

FIGURE 6 further indicates that the metal frame 39 and pawl 32 are U-shaped. The two lateral parts of pawl 32 are provided with corresponding recesses 40 forming equal detents 41 and with guide edges 42 above these recesses and equal noselike projections 43 below them. Recesses 40 are adapted to receive a pivot pin 44 for a control lever 45 which has likewise a U-shaped cross section. This control lever 45 has an upper arm 46 which

is acted upon by a compression spring 47, the lower end of which rests upon the bottom 48 of a recess 49 in the housing part 1. The ends of pivot pin 44 are slideable and guided within slots 50 in the metal frame 39, as may be seen particularly in FIGURE 6. The two lateral parts of control lever 45 have corresponding bores in which short pivot pins 51 on a one-armed lever 52 are pivotable. Lever 52, in turn, is pivotably connected by a pin 53 to the contact bridge 8. As illustrated in FIGURE 1, contact bridge 8 is stamped so as to form a central rectangular or L-shaped part 54 which carries the contacts 7 and 9, and front and rear parts 54' which are partly separated by slots from the central part 54 and are bent in the direction opposite to the central part so that all three parts together form a bearing into which the pivot pin 53 may be inserted. As may be seen in FIGURE 4, the opposite ends of pin 53 are slideable in corresponding grooves 55 in the two housing parts. The two lateral parts of control lever 45 are provided with notches 56 constituting stop projections into which a pair of small lateral projections 58 on a carrier member 57 may engage during the downward movement of the latter when the switch mechanism is in its off position as illustrated in FIGURE 4. As shown in FIGURE 2, the carrier member 57 is pivotably mounted by pivot pins 59 on a part 60 which is rigidly secured to the lower end of the control rod 62, and it is acted upon by a small compression spring 61 which tends to maintain it in the position as shown in full lines in FIGURE 2. The two sides of part 60 carry projections 60' which are slideable in corresponding grooves 62' in the two parts of the housing so as to guide the control rod 62. The upper end of the control rod 62 is rigidly secured to a pushbutton 63 which is guided within an externally threaded bushing 64 and is acted upon by a cut-off spring 65 which is wound around the control rod 62 and the lower end of which rests on an insulating washer 66 which is held on an inner flange 67 of the housing part 1.

Bushing 64 carries a nut 68 and a curved spring washer 69, and its lower end is riveted to a metal plate 70. As shown in FIGURE 3, the outer ends of this plate 70 are provided with T-shaped projections 71 which, when inserted into corresponding recesses in the right upper edges of both parts of the housing as indicated in FIGURE 7, secure this metal plate 70 rigidly to the housing when the two parts thereof are secured to each other. Plate 70 is preferably separated from the upper side of the two housing parts by an insulating strip 72.

The operation of the overload circuit breaker as previously described is as follows:

If an excess current occurs when the circuit breaker is in its on position, as illustrated in FIGURE 1, the bimetal strip 16 will be heated and will thereby bend toward the right of its position as shown in FIGURE 1 so as to press against the knob 29 of insulating material and thereby to pivot the release lever 26 in a counter-clockwise direction. Arm 33 of pawl 32 then slides off the shoulder 31 on the release lever 26 so that pawl 32 is released from its locked position. Spring 47 which presses against the arm 46 of control lever 45 then moves this lever upwardly from the position as shown in FIGURE 1. The pivot pin 44 of lever 45 thereby pivots the pawl 32 in the clockwise direction about its axis 38 and lever 45 lifts the contact bridge 8 so that its contacts 7 and 9 disengage from the fixed contacts 6 and 10 and the circuit within the circuit breaker is interrupted. This movement of control lever 45 is supported by the cut-off spring 65 which maintains the surfaces 73 of the U-shaped carrier member 57 in engagement with the pivot pin 44 when the switch mechanism is in the on position according to FIGURE 1, and which becomes effective when pawl 32 is released by the release lever 26 so that the carrier member 57 then moves the pivot pin 44 upwardly and pivots the pawl 32 in the clockwise direction.

If a short-circuit current occurs, the magnet core 19

is energized and its extensions 22 and 23 then pull up the armature 24 and thereby pivot the release lever 26 in the counterclockwise direction from the position as shown in FIGURE 1 so that the circuit breaker will then be released in the manner as previously described. A trip-free release will occur even if the pushbutton 63 is held down or jammed in the depressed position according to FIGURE 1, since in this position there is no connection between the pushbutton 63 and the control rod 62 or the parts which are secured thereto, especially the carrier member 57, and the control lever 45.

At each release of the circuit breaker the arm 46 of control lever 45 is pressed by spring 47 against an inclined surface 74 in the manner as shown in FIGURE 4. When the switch mechanism is in this off position, the notches 56 in the control lever 45 are in vertical alignment with the projections 58 on the carrier member 57. Consequently, if the pushbutton 63 is then depressed, the projections 58 engage into the notches 56 and thereby move the control lever 45 together with the contact bridge 8 downwardly. However, the contacts 7 and 9 on the contact bridge 8 will not as yet engage with the fixed contacts 6 and 10 even though the pushbutton 63 is depressed to its lowest possible position. During this downward movement of the control lever 45 its pivot pin 44 slides along the guide edges 42 of pawl 32 until it hits against the noses 43 of the pawl and thereby pivots pawl 32 in the counterclockwise direction about its axis 38 until the detents 41 of pawl 32 slide over the pivot pin 44 of control lever 45. At the same time, the release lever 26 is pivoted by the torsion spring 34 so that its shoulder 31 engages with the arm 33 of pawl 32. If the operator of the circuit breaker then takes his finger off the pushbutton 63, the projections 58 on the carrier member 57 disengage from the recesses 56 in control lever 45 so that under the action of the compression spring 47 this control lever will be pivoted with a rapid motion about its pivot pin 44 in the recesses 40 of pawl 32 and the contacts 7 and 9 of contact bridge 8 will be moved likewise with a rapid motion into engagement with the fixed contacts 6 and 10. This engagement of the bridge contacts 7 and 9 with the fixed contacts 6 and 10 is so rapid as to be instantaneous. It occurs as soon as the projections 56 which define the notches 56 slide off the projections 58 on the carrier member 57.

When the circuit breaker is in the on position as illustrated in FIGURE 1, the necessary contact pressure between the associated contacts 6, 7 and 8, 9 is produced by the compression spring 47. In this on position, the notches 56 are located outside of the area of motion of the projections 58 on the carrier member 57 so that an additional attempt to depress the pushbutton 63 cannot have any effect upon the on position of contact bridge 8 or upon the spring 47.

If the circuit breaker according to the invention is to be switched off by hand, it is merely necessary to pull on the pushbutton 63 which is for this purpose provided with a flange 63'. The upper laterally projecting surfaces 73 of the U-shaped carrier member 57 then engage upon the pivot pin 44 of control lever 45. Since this pivot pin 44 is at this time locked in a fixed position by pawl 32, the carrier member 57 will be pivoted about the pivot pins 59 to the position as indicated in FIGURE 2 in dot-and-dash lines. At this pivoting movement, a projection 75 on the lower end of carrier member 57 hits against the armature 24 and thereby pivots the release lever 26 in the counterclockwise direction from the position as shown in FIGURE 1 so that the circuit breaker is then released in the manner as previously described.

The overload circuit breaker according to the invention has very small outer dimensions which are actually only one half of those as shown in the drawings. It may be employed for rated currents up to 100 amp., and for short-circuit currents at a direct voltage of 24 volts up to 10,000 amp., and for low-voltage direct current cir-

cuits and medium-voltage alternating current circuits up to approximately 500 volts.

Although my invention has been illustrated and described with reference to the preferred embodiment thereof, I wish to have it understood that it is in no way limited to the details of such embodiment but is capable of numerous modifications within the scope of the appended claims.

Having thus fully disclosed my invention, what I claim is:

1. An overload circuit breaker comprising a housing, switch element provided within said housing and including a control rod slidable longitudinally of itself within said housing, a pushbutton secured to one end of said control rod and projecting from said housing for moving said circuit breaker to the on position, a carrier member mounted on the other end of said control rod, a pivotable control lever having a pivot pin, formations on said housing guiding said pivot pin for slidable displacement laterally of its axis, a contact bridge mounted on said control lever and movable from an off position to an on position and vice versa, a pawl pivotally mounted on said housing adjacent said formations and engageable with said pivot pin of said control lever to latch said pin in a fixed position when said contact bridge is in its on position, a release lever pivotally mounted in said housing and releasably engaging and maintaining said pawl in its latching position, excess current responsive means operable to pivot said release lever to its pawl releasing position, said control lever having a stop projection thereon located outside the path of movement of said carrier member when said contact bridge is in its on position and located within said path of movement when said contact bridge is in its off position, a pair of fixed contacts, and spring means acting upon said control lever and producing a constant contact pressure of said contact bridge against said fixed contacts when said pivot pin is in said locked position and moving said control lever, together with said contact bridge, to said off position when said pivot pin is released by said pawl.

2. An overload circuit breaker as defined in claim 1, in which said housing has an inclined surface, said control lever being pressed by said spring means against said surface when said circuit breaker is switched off, whereby said control lever is moved to a position in which said stop projection is located within the path of movement of said carrier member.

3. An overload circuit breaker as defined in claim 1, in which said pair of fixed contacts are mounted in said housing at a right angle to each other, said contact bridge being pivotably mounted on said control lever and having a substantially L-shape and being adapted to bridge said pair of fixed contacts.

4. An overload circuit breaker as defined in claim 3, further comprising a one-armed lever pivotably mounted on said control lever and having a free end, and a second pivot pin, said contact bridge being pivotably mounted by said second pivot pin on said free end, the opposite walls of said housing having corresponding grooves therein extending within the bisector of said right angle in which said fixed contacts are disposed relative to each other, the two ends of said second pivot pin being slidable and guided within said grooves.

5. An overload circuit breaker as defined in claim 4, in which said contact bridge is stamped so as to form a substantially L-shape central part and a lateral part on each side of said central part and partly separated therefrom by slots and bent in the opposite direction to said central part so that all three parts together define a bearing hole, said second pivot pin extending through said bearing hole and through corresponding holes in said free end of said lever.

6. An overload circuit breaker as defined in claim 1, in which said formations comprise slot means in said hous-

ing extending in the direction of movement of said pushbutton and said control rod.

7. An overload circuit breaker as defined in claim 5, in which said pawl has a detent thereon adapted to engage with and to lock said pivot pin of said control lever, said pawl having a guide edge for said pivot pin of said control lever at one side of said detent and a nose projecting at the other side of detent adapted to engage with said pivot pin for pivoting said pawl to its locking position.

8. An overload circuit breaker as defined in claim 1, in which said release lever has two arms, an electromagnet having a magnet core and an armature for electromagnetically releasing the circuit breaker, one of said arms of said release lever forming said armature, and a setscrew screwed through the other arm, said setscrew having a head of insulating material, and a bimetal strip engageable with said head so as to pivot said release lever for effecting a thermal release of the circuit breaker.

9. An overload circuit breaker as defined in claim 1, in which said carrier member is pivotably mounted on said control rod, a spring acting upon said carrier member, said carrier member being pivoted against the action of said last spring by said pivot pin of said control lever when locked by said pawl and when said pushbutton is manually pulled outwardly of said housing, said carrier member, when being thus pivoted, acting upon said release lever so as to pivot the same and thereby to release the circuit breaker.

10. An overload circuit breaker as defined in claim 8, further comprising a connecting bar carrying one of said fixed contacts and having a part extending substantially parallel to said bimetal strip, said bimetal strip and said part of said connecting bar being longitudinally slotted and connected to each other so as to form at least one coil winding, said magnet core extending through said slots.

11. An overload circuit breaker as defined in claim 6, further comprising a metal frame mounted in corresponding recesses in the opposite walls of said housing and containing said slots for guiding said pivot pin of said control lever, said pawl being pivotably mounted in said frame.

12. A pushbutton-actuated overload circuit breaker comprising a housing, a control rod slidably longitudinally of itself within said housing, a pushbutton on the outer end of said control rod, a carrier mounted on the inner end of said control rod, a pivotable switching lever having a pivot pin, formations on said housing extending in

the direction of movement of said control rod and said pushbutton and guiding said pivot pin for slideable displacement laterally of its axis, a contact bridge having an articulated connection to said switching lever at a point on the latter spaced from its pivot axis, a pair of stationary contacts bridged by said contact bridge in the on position of said circuit breaker, a pawl pivotally mounted on said housing adjacent said formations and engageable with said pivot pin of said switching lever to latch said pin in a fixed position when said contact bridge is in its on position, a spring acting on said switching lever at a point thereon spaced from its pivot axis and maintaining the contact pressure between said contact bridge and said stationary contacts, said spring, upon release of the pivot pin of said switching lever by said blocking pawl, biasing said switching lever, together with said contact bridge, to the off position in which said contact bridge is disengaged from said switch contacts, and an abutment in said housing, said switching lever being pressed against said abutment by said spring in the off position of said contact bridge, said switching lever being formed with a recess which, in the off position of said contact bridge, is in the range of movement of said carrier and, in the on position of said contact bridge, is outside the range of movement of said carrier, said carrier, upon inward movement of said control rod, engaging in said recess to pivot and switching lever toward the on position of said contact bridge, said carrier, upon release of said pushbutton, releasing said switching lever for snap swinging to the on position, in which said contact bridge bridges said fixed contacts, under the action of said spring, a release lever pivotally mounted in said housing, said pawl, under the action of said spring exerted through said switching lever upon said pawl, engaging said release lever and pivoting the same into a pawl latching position, and excess current-responsive means operable to pivot said release lever to a position releasing said blocking pawl.
